UNITED STATES PATENT OFFICE.

CHARLES MACKO, OF CHICAGO, ILLINOIS, ASSIGNOR TO GEORGE G. RICHTER, OF CHICAGO, ILLINOIS.

NECKTIE.

Application filed February 16, 1924. Serial No. 693,210.

To all whom it may concern:

Be it known that I, CHARLES MACKO, a citizen of the United States, and a resident of Chicago, Cook County, Illinois, have invented an Improvement in Neckties, of which the following is a specification.

This invention relates to neckties, and with regard to certain more specific features, to a reversible bow tie.

10 Among the several objects of the invention may be noted the provision of a simple and durable necktie construction; and the provision of a reversible tie which is inexpensive in construction and readily operated by the wearer. Other objects will be in part obvious and in part pointed out hereinafter.

15 The invention accordingly comprises the features of construction, combinations of 20 elements, and arrangements of parts, which are exemplified in the constructions herein-after described and the scope of the application of which will be indicated in the following claims.

25 In the accompanying drawings, in which is shown one of various possible embodiments of this invention,

Fig. 1 is a front elevation of the tie applied to a collar;

30 Fig. 2 is a top plan of the tie, showing in dotted lines a second position for the band; and

Fig. 3 is a vertical section on the line 3—3 of Fig. 2.

35 Similar reference characters indicate corresponding parts throughout the several views of the drawings.

Referring now more particularly to Figs. 1 and 2, there is illustrated at 1 a necktie having two bows 3, 5 located back-to-back, and preferably of substantially equal size, so that the bow which is visible at the moment serves to hide the other bow.

40 Encircling the bows is a loop 7. This loop is sewed to each bow. The loop may be of two materials, each extending half way around the loop, so that the material of the loop will harmonize with the bow that is visible at the moment. Or the loop may 45 be of a single material that harmonizes with the material of both bows.

An elastic band 9 passes within the loop 7 and around the wearer's collar 11. A hook 13 engages an eye 15 in the usual manner, to hold the band taut when in use. A

buckle 17 is adjustable to vary the tension of the band.

In solid lines in Figs. 2 and 3 is shown the position of the parts for the display of the bow 3.

When it is desired to display the bow 5, the wearer simply slips the band 9 around the loop until the band reaches the opposite side of the loop, as indicated in dotted lines at 9 in Figs. 2 and 3.

60 Since the loop 7 need be fastened to the bows 3, 5 at only one point, such as the bottom of the loop as shown in Fig. 3, the top of the loop (Fig. 3) is not secured to the bows, and it is thus by a counter-clockwise 65 movement (Fig. 3) of the band 9, half way around the loop 7, that the above described reversal is effected.

65 Or, stated another way, the reversal may be effected by moving the bows and loop 75 with respect to the band. That is, considering Fig. 3, the reversal may be effected by keeping the band 9 in its solid-line position, and then shifting the bows and loop in a clockwise direction until the bows and loop 80 have rotated 180 degrees, the band remaining under the loop. This method of reversal is easily effected when the tie is in position on the wearer's collar.

85 In view of the above, it will be seen that the several objects of the invention are achieved and other advantageous results attained.

90 As many changes could be made in carrying out the above constructions without departing from the scope of the invention, it is intended that all matter contained in the above description or shown in the accompanying drawings shall be interpreted as illustrative and not in a limiting sense.

95 I claim:

1. A reversible necktie comprising two bows positioned back-to-back, a loop encircling the bows and secured to each bow, a band within the loop and adapted to pass 100 around the wearer's collar, the band having a slidale connection with the loop whereby it may be slid around within the loop to expose one or the other of said bows.

105 2. A reversible necktie comprising two bows positioned back-to-back, a loop encircling the bows and secured to each bow, a band within the loop and adapted to pass around the wearer's collar, the band having a slidale connection with the loop whereby 110

it may be slid around within the loop to expose one or the other of said bows, the loop being of two materials each extending half way around the loop and respectively harmonizing with the bow that is displayed when said half of the loop is displayed.

3. A reversible necktie comprising two bows positioned back-to-back, a loop encircling the bows at their mid-point and secured to each bow, a band within the loop and adapted to pass around the wearer's collar, said band having a slidable connection with the loop, the loop being secured to the bows

at only one point to form a slidable connection between the loop and the band, 15 whereby the band may be slid around within the loop to expose one or the other of said bows; the loop being of two materials each extending half way around the loop and respectively harmonizing with the bow 20 that is displayed when said half of the loop is displayed.

In testimony whereof, I have signed my name to this specification this 13th day of Feb., 1924.

CHARLES MACKO.
